UNITED STATES PATENT OFFICE.

SAMUEL B. SWIFT, OF KNOXVILLE, TENNESSE

ENVELOP.

No. 915,806.

Specification of Letters Patent. Patented March 23, 1909.

Application filed August 6, 1907. Serial No. 387,303.

To all whom it may concern:

Be it known that I, SAMUEL B. SWIFT, a citizen of the United States, residing at Knoxville, in the county of Knox and State of Tennessee, have invented a new and useful Envelop, of which the following is a specification.

The invention relates to improvements in envelopes.

10 The object of the present invention is to improve the construction of envelopes and to provide a simple, efficient, and comparatively inexpensive envelop having means for effectually preventing it from being opened without detection.

With these and other objects in view, the invention consists in the construction and novel combination of parts hereinafter fully described, illustrated in the accompanying 20 drawing, and pointed out in the claims here-to appended.

In the drawing: Figure 1 is a rear elevation of an envelop constructed in accordance with this invention. Fig. 2 is a longitudinal 25 sectional view of the same taken on the line X—X of Fig. 1. Fig. 3 is a transverse sectional view taken on the line y—y of Fig. 1. Fig. 4 is a plan view of the envelop showing the same before it is folded.

30 Like numerals of reference designate corresponding parts in all the figures of the drawing.

The envelop consists of a single sheet of paper or other suitable material, and the central portion thereof constitutes the front 1 of the envelop, which is provided with upper and lower side flaps 2 and 3 and end flaps 4 and 5, the body or blank being folded on the dotted lines a and b of Fig. 4 to form the 40 envelop.

The end flaps are tapered as clearly illustrated in Fig. 4 of the drawing, and the end flap 4 is provided with a reduced longitudinal extension 6, having a gummed outer portion 7 and provided at its inner end with a transverse slit or slot 8 to receive a tongue 9 of the other end flap 5. The tongue 9, which extends longitudinally from the end flap 5, is provided with a substantially arrow-shaped head 10, which is adapted to be passed through the slot or opening 8 of the extension. The laterally extending portions of the head may be folded inwardly on the tongue to facilitate the introduction of the

tongue in the slot 8, and after the head 10 55 has been passed through the slot 8 the sides of the head may be unfolded.

The gummed portion 7 of the extension is adapted to engage the end flap 5 adjacent to the inner end of the tongue 9, and any attempt to open either end of the envelop will tear or injure the tongue and the extension which will indicate by such injured condition that the envelop has been tampered with or opened. 60

The upper side flap 2, which is tapered, has its side and end edges 11 and 12 gummed for engaging the exterior of the lower side flap 3, which has its side edges 13 gummed to engage the outer faces of the end flaps 4 65 and 5. The lower side flap is provided at its end with a slot or slit 14 disposed longitudinally of the envelop, and adapted to receive a concealed breakable sealing strip 15, constructed of thin tissue paper, or other 70 suitable material, and secured at its end 16 by adhesive material to the inner face of the upper side flap 2 adjacent to the hinged edge thereof. The sealing strip, which is disposed transversely of the envelop, has its other end 75 17 secured between the side flaps 2 and 3 by the gum or other adhesive material at the end of the upper side flap 2. 80

In practice, after the side flaps have been folded down upon the end flaps and sealed, 85 the outer end of the sealing strip will be torn off close to the end edge of the upper flap 2, the end 17 of the sealing strip being shown protruding slightly in Figs. 1 and 3 of the drawing to illustrate the construction more 90 clearly. The outer face of the lower side flap 3 is provided adjacent to its hinged edge with a roughened weakened surface formed by a plurality of indentations or partial perforations 18, and the upper side flap is provided at its outer edge with a similar roughened and weakened portion 19. These portions 18 and 19 are designed to be formed by a punch or stamp similar to those used for punching checks, drafts, etc., for preventing 95 the same from being raised. The roughened portions 18 and 19 enable the mucilage or other material to adhere better to the paper, and by weakening such portions, they will readily separate from the adjacent portions 100 of the envelop should an attempt be made to surreptitiously open the same, and will indicate such fact. Also, any attempt to open 105

the envelop will tear or otherwise injure the concealed sealing strip 15, or the tongue and the extension of the end flaps.

Having thus fully described my invention, 5 what I claim as new and desire to secure by Letters-Patent is:

1. An envelop provided with opposite end flaps, one of the end flaps being provided with an extension having a gummed outer portion and provided at the inner portion with a slot, and the other end flap being engaged by the gummed portion of the extension and having a tongue arranged to be passed through the slot of the extension and 10 provided with an enlarged head for preventing the withdrawal of the tongue, upper and lower side flaps, and a transversely disposed sealing strip secured at one end to the upper side flap and engaging the lower side flap 15 and having its free end arranged in position to be secured by the upper side flap to the seal of the envelop.

2. An envelop comprising a front, and an end flap having a slot, an opposite end flap provided with a tongue arranged to be passed through the slot and having a head, upper and lower side flaps, one of the side flaps having a slot, and a transversely disposed sealing strip constructed of thin breakable material and secured at one end to the upper side flap and arranged to be passed through the slot of the lower side flap, the free end of the sealing strip being located exteriorly of the side flap in position to be secured to the same by the upper side flap upon the sealing of the envelop.

3. An envelop comprising a front, an end flap provided with an extension having a gummed outer portion and provided at the 35 inner portion with a slot, an opposite end

flap provided with a longitudinal tongue having an arrow-shaped head and arranged to be passed through the said slot, upper and lower side flaps provided with weakened roughened portions, the lower side flap having a slot, and a transversely disposed sealing strip constructed of thin breakable material, and secured at one end to the other side flap and arranged to be passed through the slot of the lower side flap, the free end of the sealing strip being arranged exteriorly of the lower side flap in position to be secured to the same by the upper side flap in the sealing of the envelop.

4. An envelop comprising a front, an end flap provided with an extension having a gummed outer portion and provided at the inner portion with a slot, an opposite end flap provided with a longitudinal tongue arranged to be passed through the said slot, the latter end flap being also engaged by the gummed portion of the extension, upper and lower side flaps, the lower side flap having a slot, and a transversely disposed sealing strip constructed of thin breakable material and secured at one end to the other side flap and arranged to be passed through the slot of the lower side flap, the free end of the sealing strip being located exteriorly of the lower side flap in position to be secured to the same by the upper side flap in the sealing of the envelop.

In testimony, that I claim the foregoing as my own, I have hereto affixed my signature in the presence of two witnesses.

SAMUEL B. SWIFT.
